APPARATUS FOR ROAD BUILDING

Enoch Berg Jorgensen, Los Angeles, Calif., assignor, by means assignments, to Viber Company, Los Angeles, Calif., a corporation of California

Application September 4, 1937, Serial No. 162,511

9 Claims. (Cl. 94—40)

This invention relates to a machine and a method for road building and in particular to a machine and a method for stabilizing sub-grade or base-forming materials and for laying a stabilized subgrade stratum as a base for a surface stratum.

It is now recognized that the durability of surfaced roadways depends to a large extent upon the original provision and continued maintenance of a high weight-bearing capacity of the sub-grade base for the road under all conditions of weathering and use. It is also well known that the condition of the subgrade base, particularly for Portland cement concrete surfaces, both as to the load-bearing capacity and as to the moisture content at the time the concrete mass is laid, is an important factor effecting the quality and durability of the concrete slab. The treatment of the indigenous soil or other materials which are available for the construction of the sub-grade stratum for surfaced roads has come to be called "stabilization" or "sub-grade stabilization", and the terms generally refer not only to the control of the moisture content at the time of compaction but also to the improvement of the load-bearing capacity of the indigenous materials by the addition thereto of admixture materials. These admixture materials which are commonly used are finely divided bonding soil, clay, powdered and granular rock, cement, sand, chemicals such as calcium chloride or sodium chloride, organic and bituminous binding materials, and water.

The indigenous materials in a given location are usually examined and suitably tested to determine what available admixture materials will best serve the purpose of sufficiently stabilizing, both from a physical as well as economical point of view. Depending upon the local conditions, admixture materials are then prescribed which will give the desired load-bearing capacity. The moisture content of the materials forming the sub-base is important because in placing the material on the roadbed, and compacting it, there is an optimum moisture condition—neither too wet nor too dry—which facilitates the handling of the material. In sub-bases for concrete surfacing, it is particularly important not only that the sub-grade base material be stabilized as to the assortment of particle sizes and their binding or holding together, (both of which effect the load-bearing capacity) but also that the sub-grade base, in its finished form, ready for the laying thereon of the concrete mix, must be neither too wet nor too dry

because these conditions effect the warping and expansion of the surface stratum during its setting.

The treatment or preparation of the material for the sub-grade base, the distribution of it again on the roadbed, and its consolidation after placement, are usually carried out by hand labor, or hand labor assisted by shovels, plows, harrows, rakes, drags, and the like, by which the material is manipulated over and over or back and forth. in piles or rows on the roadbed, until the admixture is mixed in, and the water content equally adjusted, usually by sprinkling and further mixing on the road. Such methods are costly, and do not usually give uniform results, and the moisture content of the materials in particular is subject to the vagaries of the weather, because of the long manipulating time required with these simpler tools and machines to effect the uniform mixing in of the required water.

The general object of this invention is therefore to provide an improved apparatus and method for continuously treating the materials to be used for the sub-grade base for a surfaced roadway or pavement to stabilize the same and simultaneously continuously forming a sub-grade stratum. A further object is to provide an improved apparatus and method for forming the sub-grade base for a pavement or a roadway in which the moisture content of the material to be used for said sub-grade will be maintained during forming of the sub-base. Another object is to provide an improved apparatus and method by which the indigenous materials may be continuously mixed with admixture materials for stabilizing the same. Still another object is to provide a machine and a method by which a treated sub-grade soil mixture may be continuously distributed and compacted in place on the roadbed. Further objects of the invention will appear hereinafter.

The invention consists in the method described hereinafter, and resides also in the combination of parts all of which contribute to produce an efficient sub-base treating and placing machine.

In the drawings:

Fig. 1 shows a longitudinal sectional view of my machine, representing the same in the act of simultaneously picking up road material, mixing it with admixture, and redepositing it in compacted form in place as the sub-grade stratum of a roadway;

Fig. 2 shows a plan view of my machine with parts broken away to show detail;

Fig. 3 shows a sectional view through the line 3-3 of Fig. 1;

Fig. 4 shows a portion of the longitudinal sectional view, representing an alternative structure for compacting the stabilized mixture on the roadbed.

Fig. 5 is an isometric view showing in more detail a portion of the grid structures.

In the preferred embodiment of my invention as illustrated in Figs. 1, 2, and 3 the main or carriage frame 11 is constructed of side members 12, end members 13, and intermediary cross-members 14, and is supported for movement along the roadway on pre-laid track members 15, by front flanged wheels 16 and driven rear flanged wheels 17. Scraper means 18 attached to the frame in front of the front wheels 16 serve to sweep debris off the track in advance of the machine.

20 Mounted on the main frame is an internal combustion engine 19 associated with a clutch 25 and clutch lever 26 and power transmission mechanism 28 including a gear-shift lever 21. Mounted for actuation by a counter shaft 24 from said transmission 28 is an electrical generator 22 to provide electrical energy for operating the high speed motor 88 which operates the vibrating element 82. The counter drive shaft 24 also drives the conveyors and mixer, in 30 synchronism with the forward movement of the machine when it is in position to operate, through the bevel gear 88.

The machine is propelled through the rear wheels 17 on the rear axle 27 by means of a 35 geared drive 28 operatively connected through the clutch 25 and the transmission 28 to the engine 19. Supported below the main frame 11 is a secondary frame 38 which extends across the roadway or strip of roadway and is adapted to be 40 raised and lowered relative to the main frame by jacks 31 represented as located at the corners of the secondary frame, the jacks being adapted to position the secondary frame up and down by 45 operation of the hand wheels 32 connected with the threaded shafts 33 in the brackets 28. Mounted on the secondary frame 38 is a scooping or picking-up mechanism having nearly horizontal cutting blades 34 at the forward edge of each member of a gang of parallel inclined channels or troughs 35. Moving upwardly in these 50 troughs 35 are cross-wise vanes or propelling members 36 attached to an endless conveyor chain 37 operating over sprocket-wheels 38 on the shaft 47 above the lower end of the incline and driven 55 sprocket-wheels 39 above the upper end of the incline. The sprockets 39 are driven through the pulley 46 on the shaft 45 by means of a belt 48 and pulley 41 on the cross drive shaft 24, an adjustable idler pulley 44 attached to the main 60 frame being provided for belt length adjustment when raising and lowering the cutting blades 34. The scooping mechanism is preferably made in lengthwise sections, each having a separate cutting blade 34 and a separate inclined channel member 35 with side partitions 42 and propelling members 36 extending across the full width of the roadway and being notched as shown at 43 to pass the partitions 42. The upper ends of the troughs 35 are pivotally supported on the shaft 45, 65 and the lower ends of the troughs, near the cutting blades 34, are held together as a scooping unit by the cross member 39, which is adjustably positioned from the secondary frame 38 by the screw jacks 48 and the yoke members 49. At the 70 upper end of the flight conveyor is a cross-screw

conveyor consisting of a spiral screw member 54 mounted on a shaft 51 in an open housing 52. This cross-screw conveyor is disposed a short distance away from the discharge of the flight conveyor and its housing 52 forms, with the adjustable valving member 53, a throat through which passes a selected or accepted portion of the road material which is discharged from the flight conveyor. The housing 52 of the cross-screw conveyor is open on the side adjacent the discharge end of the flight conveyor and serves to carry away any surplus material which does not pass through the throat between the adjustable valving member 53 and the screw conveyor housing 52. The member 53 is pivotally supported at one end to the shaft 48 on the under side of the discharge or upper end of the flight conveyor and is adapted to be adjusted by the threaded shaft 54 and the hand wheel 55. The screw conveyor discharges the overflow material, which does not pass through the throat, to the downwardly inclined discharge spout 56 which spills the surplus material at the side of the roadway. Beneath the throat opening is a hopper 58 extending across the roadway and supported by the secondary frame 38. The bottom of the hopper 58 consists of a reciprocable grid 59 made up of bars 57 and the hopper including the grid bars is reciprocated at right angles to the linear position of the bars by a crank shaft motion shown in detail in Fig. 3. Beneath the hopper 58 is a stationary grid member 60 having enclosing walls 61 and supported on the secondary frame. Beneath this stationary grid member is a second reciprocable grid member 62 with enclosing walls 61a and beneath it is a second stationary grid member 63 with enclosing walls 61b. The enclosing wall members 61, 61a, and 61b are arranged to enclose the grid members but allow relative motion of the separate parts, and a discharge chute 62 across the full width of the roadway, directs the discharged and treated material.

Referring particularly to Fig. 3, the grid members 59 and 62 are reciprocated by the crank shaft 64 and the arms 65 to the connecting members 66. The crank shaft 64 is driven through the worm gear 67 by the worm 68 on the shaft 70. The helical gear 68 on a straight shaft extension of the crankshaft 64 drives the helical gear 69 attached to the shaft 51 for the spiral conveyor. The shaft 70 is operatively connected with the cross-drive shaft 24 through the bevel gears 85 and 86 and shaft 87 which is slip-keyed to the pinion bevel gear 88 driven by the bevel gear 89 at one end of the cross-drive shaft 24. The slip-keying of the shaft 87 in the pinion bevel gear 88 allows for the driving of the mixer grid bars and the cross conveyor when the secondary frame 38 is at any elevation relative to the main frame 11.

Attached by the bracket member 83 to the secondary frame 38 beneath the inclined trough is a means for generating high frequency vibration consisting of a high speed motor 88, a flexible shaft and flexible housing 81, and a rotary vibratory mechanism at the end of the flexible shaft in a tubular casing 82, the whole being mounted in such a position that the vibratory tube 82 is submerged in the discharged material from the grids. The rotary vibratory mechanism may be made in accordance with my Patent No. 2,061,943, or of other construction to give high frequency vibration of the order of 10,000 per minute. The electrical power for actuating the high speed motors is received by electrical con-

nectors 84 which are in turn connected to the electrical generator 22. As many vibratory units as are required to properly compact the material, are disposed across the width of the roadway. 5 Attached rearwardly of the end of the tubular vibratory casing 82 and of the position of discharge of treated material from the mixer is a screed member 90 pivotally attached at 81 to the discharge chute 82. The screed member 90 10 is adjustably positioned by the worm 94 operating in the segment of a spiral gear 99, by the turning of the hand wheel 95 having a shaft 96 and a spring balanced attachment means 97 to the secondary frame 30. Supported on the secondary frame 30 is a hopper 101 having a discharge spout 102 or a series of discharge spouts extending across the full width of the roadway, and a control valve 103 in the spout for regulating the delivery of material into the mixer hopper 58.

20 Referring specifically to Fig. 4, an alternative means of compacting the deposited material is indicated in the form of a weighted roller 110 having a shaft 111 and a journal mounting 112 adjustably supported on the secondary frame 30 25 through spring balanced bars 113 in a sleeved bracket 114. The roller is positioned rearwardly of the discharge chute 82 from the mixer.

My method of road building as particularly related to the preparation of the sub-base consists generally of the steps of cutting the roadbed to a desired lower level, picking up the loose material lying on the roadway above this predetermined lower level, dividing out a usable portion of this loose material and discarding the remainder, mixing the usable portion with a suitable admixture for stabilizing it, evenly distributing the mixture on the prepared lower level of the roadbed and then compacting the mixture to form a stabilized sub-grade base. The 40 manner of operating the particular embodiment of my invention as described above is as follows:

Preliminary to the use of my apparatus, side forms for the desired roadway including track members are placed along the roadway, after the 45 usual cutting, filling and initial grading of the roadway has been completed. The material between the side forms which may be indigenous soil or imported material, is then loosened, if necessary, by any convenient means such as by hand picks and shovels or by machine operated plows or harrows, and a suitable amount of moisture is added by sprinkling. Admixture material, other than water, may also be added at this stage of the operation providing it is reasonably well distributed over the road surface 50 although I prefer to use the means as hereinafter described which operates simultaneously with the other parts of my stabilizing machine. With the roadway ahead of my machine previously prepared as above described, the cutting blades attached to the lower edge of the inclined conveyor means are lowered to a position so that they will scoop up the loose soil or road materials to a predetermined lower level, by adjustment of the 55 elevation of the secondary frame by means of the jacks and also by the adjusting means which regulate the position of the cutting edge. As the carriage is advanced, the loose soil is scooped up by the cutting blades onto the conveyor trough along which it is propelled by the flight conveyor 60 blades to the throat. The flight conveyor is actuated in synchronism with the forward movement of the carriage by the motor through the driving means as described in detail above. The 65 throat adjusting member at the upper end of the

flight conveyor is regulated so that the desired proportion of soil drops into the mixer hopper and the excess overflows into the housing for the cross-screw conveyor and is discarded at the side of the roadway. The accepted portion is stabilized by mixing it with the proper amount of a suitable admixture material which is added to the hopper of the mixer through the spout from the admixture hopper. In the mixer the ingredients are thoroughly mixed and any lumps are 10 disintegrated by the action of the reciprocating grid bars.

The stabilized mixture is then discharged through the chute onto the roadbed in a layer which gives, upon compacting, the desired thickness of the sub-grade base. The compacting of this layer is made in the preferred form of my apparatus shown in Figs. 1 and 2 by the action of a high frequency insertible vibrator mechanism encased in a tube which is driven by means of the high speed motor which receives its electrical energy from the generator on the main frame driven by the engine of my machine. Instead of an electric generator and electric motor combination, an air compressor and a compressed air motor to drive the vibrator mechanism may be used. The mixture is packed by the vibrations to its maximum density, particularly when the vibrational energy is applied between the bottom of the roadbed and a forming member such as the screed which serves to confine the vibrating materials around the vibrator to form the desired stratum, with the vibrator tube continuously advancing with the machine.

When it is desired to transport the carriage 35 without operating the various units of the combination, the secondary frame is raised relative to the main frame, pulling all of the parts up so that they will not interfere with the movement of the machine.

Instead of the vibration to compact the stabilized mixture as it falls upon the road, a weighted roller may be substituted as indicated in Fig. 4, the other operations being substantially as described for the preferred embodiment.

While I have described my method of making a stabilized sub-base for a roadway by reference to a preferred apparatus of my invention, I do not wish to limit myself to this particular apparatus since it is possible to perform the method by other well known apparatus or by hand operations, and while I have shown a preferred embodiment of my apparatus invention, I do not wish to be restricted to the particular form shown, but limit my invention only insofar as is necessitated by the prior art and the appended claims.

I claim:

1. In a sub-grade base stabilizing machine for road building, in combination, a carriage, 60 scooping means attached thereto for picking up loose road materials above a selected lower base level on the roadbed, a conveyor on said carriage for elevating the scooped-up road material, means for continuously dividing the road material discharged from the said conveyor into a 65 usable portion and a surplus portion, means for conveying the surplus portion away from the machine, means for feeding into the usable portion of the road material to be treated a predetermined proportion of a stabilizing agent, means mounted on said carriage for mixing the usable 70 road material and the stabilizing agent, means for continuously discharging the mixture from said mixing means onto the roadbed, means operable with the carriage for leveling off the dis- 75

charged mixture to a desired road level, and vibratory mechanisms attached to said carriage adapted to be dragged through said discharged mixture and below the top surface to compact it on the roadbed.

5. 2. In a sub-grade base stabilizing machine for road building, in combination, a wheeled main frame adapted to travel along a prepared roadway, a secondary frame adjustably supported below and by said main frame, scooping means attached to said secondary frame adapted for picking up loose road materials above a selected lower base level on the roadbed and having substantially horizontal cutting blades on its forward edge, conveyor means on said secondary frame for elevating the scooped-up road material, adjustable throat means for continuously dividing the road material discharged from the said conveyor into a usable portion and a rejected portion, a cross conveyor for receiving and discharging the rejected portion away from the path of the machine, mixing means mounted on said secondary frame for receiving the usable road material, valved-spout means for feeding 10 into the mixer a selected proportion of a stabilizing agent, a hopper on the secondary frame for holding the stabilizing agent, spout means for continuously discharging the mixture from said mixing means onto the roadbed beneath the machine, means operable with the wheeled main frame for leveling off the discharged mixture, and vibratory mechanisms attached to said secondary frame adapted to be dragged through said discharged mixture to compact it on the roadbed.

3. In a sub-grade stabilizing machine for road building, in combination, a wheeled main frame adapted to be propelled along a prepared roadway, motor means mounted on said main frame for propelling said wheeled main frame, a secondary frame adjustably supported below and by said main frame, a channeled inclined scoop attached to said secondary frame adapted for picking up loose road materials above a selected lower base level on the roadbed, a flight conveyor of said secondary frame for propelling the picked-up road material up the channels of said scoop, an adjustable throat for continuously dividing the road material reaching the top of said inclined scoop into a usable portion and a rejected portion, means for conveying the rejected portion away from the machine, a mixer-hopper for receiving the usable portion, means for feeding into the mixer hopper a predetermined proportion of a stabilizing agent, mixing means mounted on said secondary frame for mixing the usable road material and the stabilizing agent, means for continuously discharging the mixture from said mixing means onto the roadbed, means operable with the wheeled main frame for leveling off the discharged mixture, and vibratory means depending from the secondary frame adapted to be dragged through said discharged mixture to compact it on the roadbed.

4. In a sub-grade base stabilizing machine for road building, in combination, a carriage, scooping means attached thereto for picking up loose road materials above a selected lower base level on the roadbed, a conveyor on said carriage for elevating the scooped-up road material, means for continuously dividing the road material discharged from the said conveyor into a usable portion and a surplus portion, means for

conveying the surplus portion away from the machine, means for feeding into the usable portion of the road material to be treated a predetermined proportion of a stabilizing agent, means mounted on said carriage for mixing the usable road material and the stabilizing agent, means for continuously discharging the mixture from said mixing means onto the roadbed, means operable with the carriage for leveling off the discharged mixture, and compactor means attached to said carriage adapted to consolidate the mixture on the roadbed.

5. In a sub-grade base stabilizing machine for road building, in combination, a carriage, hopper means attached thereto for receiving loose road materials, adjustable throat means for continuously dividing the received road material into a usable portion and a surplus portion, means for conveying the surplus portion away from the machine, means for feeding into the usable portion of the road material to be treated a predetermined proportion of a stabilizing agent, means mounted on said carriage for mixing the usable road material and the stabilizing agent, and means for continuously discharging the mixture from said mixing means onto the roadbed.

6. In a sub-grade base stabilizing machine for road building, in combination, a carriage, means attached thereto for picking up loose road material above a selected lower base level on the roadbed, elevating means on said carriage for the picked-up road material, means for continuously dividing the road material discharged from the said elevator into an accepted portion and a surplus portion, means for continuously conveying the surplus portion away from the machine, disintegrating and mixing means for the accepted portion of the road materials, spout means for continuously discharging the mixed materials from said disintegrating and mixing means onto the roadbed, means operable with the carriage for leveling off the discharging mixture, and vibratory mechanisms attached to said carriage adapted to be dragged through said discharged mixture between the leveling means and the bottom of the roadbed.

7. In a sub-grade base stabilizing machine for road building, in combination, a carriage, scooping means attached thereto for picking up loose road material above a selected lower base level on the roadbed, a conveyor on said carriage for elevating the scooped-up road material, adjustable throat means for continuously dividing the road material discharged from the said conveyor into a usable portion and a surplus portion, means for continuously conveying the surplus portion away from the machine, means for feeding into the usable portion of the road material to be treated a predetermined proportion of a stabilizing agent, means mounted on said carriage for mixing the usable road material and the stabilizing agent, means for continuously discharging the mixture from said mixing means onto the roadbed, means on said carriage for evenly distributing said stabilized material on said roadbed and means for compacting the distributed material.

8. In a sub-grade base stabilizing machine for road building, in combination, a carriage, scooping means attached thereto for picking up loose road material above a selected lower base level on the roadbed, a conveyor on said carriage for elevating the scooped-up road material, adjustable throat means for continuously dividing the

road material discharged from the said conveyor into a usable portion and a surplus portion, means for continuously conveying the surplus portion away from the machine, means for feeding into the usable portion of the road material to be treated a predetermined proportion of a stabilizing agent, means mounted on said carriage for mixing the usable road material and the stabilizing agent, means for continuously discharging the mixture from said mixing means onto the roadbed, and a weighted roller means associated with said carriage for compacting material on the roadbed.

9. In a machine for treating and distributing

sub-grade base materials on a roadbed having a wheeled main frame adapted to travel along and over the roadway, a combined disintegrating, mixing and distributing means attached to said frame comprising alternately movable and stationary grid members extending transversely of the roadway and disposed one above the other, side walls for enclosing said grid members, a receiving hopper co-extensive with the upper grid member, a distributing spout co-extensive with the lower grid member and means for reciprocating the movable grid members.

ENOCH BERG JORGENSEN.
